Filed Sept. 2, 1964, Ser. No. 81,570

Term of patent 14 years

(Cl. D34—5)

Fig 1

Fig 2

Fig 3

FIG. 1 is a front elevational view showing my new design for barbell weight;

FIG. 2 is a cross-sectional view taken substantially along line 2—2 in FIG. 1; and

FIG. 3 is a side elevational view of one side of the barbell weight shown in FIG. 1.

The back of the barbell weight is substantially identical to the front thereof and the other side of the barbell weight is substantially identical to the side illustrated in FIG. 3 except that there is a continuous periphery with no circular plug therein.

I claim:

The ornamental design for barbell weight, substantially as shown and described.
